DESIGN FOR A COMBINED BROOCH AND COMPACT

Ruth L. Fisk and Augusta Abicht, New York, N. Y.

Application October 11, 1945, Serial No. 122,736

Term of patent 14 years

(Cl. D86—10)

To all whom it may concern:

Be it known that we, Ruth L. Fisk and Augusta Abicht, citizens of the United States of America, residing in New York city, county of New York, and State of New York, have invented a new, original, and ornamental Design for a Combined Brooch and Compact, of which the following is a specification, reference being had to the accompanying drawing, forming part thereof.

Fig. 1 is a plan view of a combined brooch and compact showing our new design.

Fig. 2 is an edge view thereof.

Fig. 3 is a plan view in open position.

We claim:

The ornamental design for a combined brooch and compact, substantially as shown.

RUTH L. FISK.
AUGUSTA ABICHT.
